8 Claims. (Cl. 172—240)

This invention relates to a control mechanism for reciprocable machines, such as printing presses or the like.

In reciprocable machines, such as printing presses in which the impression cylinder is moved to and fro over a stationary printing form arranged upon a horizontal bed, the carriage carrying the impression cylinder is reciprocated over the printing form by means of an electric motor. At the two outermost end positions of the machine, stationary contacts are actuated by the cylinder carriage, the supply of current to the motor, and therefore movement of the cylinder carriage, thus being stopped or reversed. These stationary contacts have the disadvantage that at different speeds of the cylinder carriage, the latter will over-run these contacts. The extent of over-running, which is dependent upon the speed at which the carriage travels, heretofore was not taken into consideration, resulting in that the cylinder carriage did not always come to rest at the same place at the actual end station.

Now the object of the present invention is to provide a positive connection between displaceably arranged terminal interrupters or reversing switches and the resistance that regulates the speed of revolution of the motor. The motor is thereby switched off or reversed, at any speed, at a position favourable to the retardation and stoppage of the cylinder carriage.

One embodiment of the invention is illustrated by way of example in Fig. 1 of the accompanying drawings, which shows in side elevation the left hand end of a printing machine equipped therewith, whereas Fig. 2 is a schematic diagram of the wiring system for a reversing switch arrangement used in connection with such machine.

On the side walls 1 of the machine are arranged toothed racks 2. Upon tracks 3 run rollers 5, supporting the carriage 4 for the impression cylinder 6. In the carriage 4 is journaled a shaft 7, on which are mounted toothed wheels 8 meshing with the racks 2. To one end shield or side plate of the carriage 4 is secured an electric motor 9. Its shaft drives a worm 10, which meshes with a worm wheel 11 secured to the shaft 7. Hence the shaft 7 is rotated by the motor 9, and accordingly the carriage 4, with the impression cylinder, travels along the racks 2 over the stationary printing form. The impression cylinder 6 runs in one working stroke from an extreme position on the right towards the left, and can be stopped after running over the printing form. It then has to run back again to the right from its left hand end position in a second

working stroke. These movements can be executed at different speeds according to the adjustment of the speed of revolution of the motor.

In order to switch off the electric motor 9 at a position corresponding to the speed of running and to the mass acceleration of the cylinder carriage the following innovation described by way of example is provided. With a switch lever 12 of a regulating resistance 13 a cable pulley 16 is connected by means of a rod 14 and a slotted lever 15. To this pulley are secured the ends of the wire 17 of a Bowden cable. The ends of the guides of the Bowden cable are secured to a casting 19 and to blocks 20 and 21, which are secured in a guiding rail 22. To the free portion of the cable wire 17 between the blocks 20 and 21 is secured a slider 23, which is movable along the rail 22. The rail 22 is pivoted to levers 26, 27, oscillatably mounted upon bolts 24 and 25 respectively. 28 is the switch pin of a known disconnecting or reversing switch 29, which controls the supply of current to the motor 9. On the cylinder carriage 4 is mounted a roller 30, which co-operates with the slider 23.

The machine operates in the following manner: When the roller 30 of the cylinder carriage 4 meets the slider 23 located in its path, the slider 23 and the rail 22 forming together switch actuating means yield downwards. In so doing the rail 22 pushes in the pin 28 of the switch 29, whereby the motor 9 is brought to a standstill or a reversal of current is effected for the return of the cylinder carriage 4. Upon the switch lever 12 of the regulating resistance 13 moving in such a direction as to increase the speed of the motor 9, the slider 23 travels, through the medium of the switch rod 14, the slotted lever 15, the cable pulley 16 and the cable wire 17, to meet the cylinder carriage 4, which is running at an increased speed. The disconnection or reversal is thereby effected earlier, that is, at a greater distance from the terminal position of the cylinder carriage. In regulating the speed of the motor 9 downwards, these operations take place in the reverse direction. For the other end of the machine a similar device is provided. With respect to the support of rail 22 in its position of rest, it is to be noted that the rail 22 permanently bears on stem or pin 28 of switch 29. Pin 28 is held, as it is conventional, by spring means (not shown) located within the switch 29, in a position in which the switch-contacts within switch 29 are disconnected from the current supply source. The current supply source RST is connected through relay 29 forming part of

- switch 29 (positioned at one end of the printing machine) to motor 9 beyond relay 29''. Relay 29'' forms part of switch arrangement 28a, 29a positioned at the other end of said printing machine. This relay 29'' is connected to current source RST ahead of relay 29' and further to motor 9. It is understood that upon engagement of carriage member 30 with the slider or terminal means 23, switch 29 or 29a is actuated by rail 5 22 on which slider 23 is adjustably arranged.
- What I claim is:
1. A control mechanism for reciprocable machines having a bed, such as printing presses, comprising a member movable along said bed, an electric motor for imparting movement to said member, a speed controller for said motor, an actuator including adjustable limit means, said limit means being located in the path of movement of said member and being coupled with 10 said controller for cooperation therewith, and means in engagement with said limit means and cooperable with said actuator for regulating the limit of movement of said member upon engagement of the latter with said limit means.
  2. A control mechanism for reciprocable machines having a bed, such as printing presses, comprising a member reciprocable along said bed, an electric motor for imparting movement to said member, a speed controller for said motor and 15 having a movable portion, a slideway disposed at said bed, terminal means shiftable on said slideway and in the path of movement of said member for engagement with the latter, said terminal means being positively connected to said movable portion of said controller to determine speed of said member in conformity with the shifted position of said terminal means, and switch means cooperable with said slideway for regulating the limit of movement of said member upon engagement of the latter with said terminal means.
  3. A control mechanism for reciprocable machines having a bed, such as printing presses, comprising a member movable along said bed, an electric motor for imparting movement to said member, a motor speed controller having a movable lever, an actuator disposed at said bed and comprising a swingable rail and terminal means adjustable and slidable on said rail, said terminal means being placed in the path of movement of said member and coupled with said lever to determine speed of said member in conformity with the adjusted position of said terminal means, and switch means for said motor, said rail resting upon said switch means and being operable therewith upon engagement of said member with said terminal means for controlling operation of said motor.
  4. A control mechanism for reciprocable machines having a bed, such as printing presses, comprising a member movable along said bed, an electric motor for imparting movement to said member, a speed controller for said motor and having a swingable lever, an actuator disposed at said bed and comprising a displaceable rail and terminal means adjustable and slidable on said rail, said terminal means being placed in the path of movement of said member and coupled with said lever for cooperation with said controller to determine movement of said member in conformity with the adjusted position of said

terminal means, and a reversing switch, said rail resting upon said switch and being operable therewith upon engagement of said member with said terminal means for controlling operation of said motor.

5. A control mechanism for reciprocable machines having a bed, such as printing presses, comprising a member movable along said bed, an electric motor for imparting movement to said member, a speed controller for said motor, 10 said controller having a swingable lever, actuating means disposed at said bed, said actuating means including a rail, terminal means slidable on said rail and positioned in the path of movement of said member, and connecting means between said lever and said terminal means for cooperation between said lever and said terminal means to position said terminal means on said rail in conformity with the position of said lever for determining the position of said terminal 15 means with relation to the speed of movement of said member, and means for switching said motor, said rail actuating said switching means upon engagement of said member with said terminal means.

6. A control mechanism for reciprocable machines having a bed, such as printing presses, comprising a member movable along said bed, an electric motor for driving said member, a speed controller for said motor, said controller having 20 a regulating lever, switch means for said motor and adjacent said bed, a rail adjacent said switch means and in contact therewith, and terminal means positioned on said rail and operatively connected with said regulating lever and positioned in the path of said member the actuation of said lever determining positioning of said terminal means according to the speed of movement of said member regulated by said lever, said rail actuating said switch means when said member during its travel engages with said terminal means.

7. A control mechanism for reciprocable machines having a bed, such as printing presses, comprising a member movable along said bed, an electric motor for imparting movement to said member, a switch for said motor, and terminal means in the path of said movable member and depressible thereby, a portion of said terminal means being connected to said controller and being adjustable with said controller for determining limit of movement of said member said terminal means being depressed by said member at said limit of its movement to actuate said switching means, said switch and said terminal means being adjacently positioned on said bed.

8. A control mechanism for reciprocable machines having a bed, such as printing presses, comprising a reciprocable member on said bed, an electric motor for imparting movement to said member, a speed controller for said motor, a switch for said motor, and switch actuating means in the path of movement of said member and operated by said latter to actuate said switch upon a predetermined movement of said member, said switch actuating means having at least a portion permanently connected with said controller for cooperation therewith to determine the limit of said movement.
